UNITED STATES PATENT OFFICE

MONTFORD M. MOORE, OF CANTON, OHIO, ASSIGNEE TO THE M. MOORE SHIRT FACTORIES CO., OF CANTON, OHIO, A CORPORATION OF OHIO

SHIRT

Application filed October 24, 1928. Serial No. 314,681.

This invention relates to wearing apparel, more particularly to shirts for outer wear and has for its object to provide, in a manner as hereinafter set forth, a shirt of the class referred to having the front of its body constructed in a manner to provide with respect to the form of shirts now generally worn for increased ventilation for the wearer.

A further object of the invention is to provide, in a manner as hereinafter set forth, a shirt of the class referred to having its body formed with a vent of a length to increase the ventilation for and to enable it to be quickly positioned on the wearer.

15 A further object of the invention is to provide, in a manner as hereinafter set forth a shirt of the class referred to having its front formed with an elongated vent opening provided by a pair of new and novel opposed 20 strips, one constituting a button carrying strip and the other a button-hole strip.

A further object of the invention is to provide, in a manner as hereinafter set forth a shirt of the class referred to having as a part 25 of its front a reinforced button carrying strip.

Further objects of the invention are to provide, in a manner as hereinafter set forth, a shirt for outer wear which is simple in its construction and arrangement, strong, durable, compact, thoroughly efficient for the purpose intended, and comparatively inexpensive to manufacture.

With the foregoing and other objects in view the invention consists of the novel construction, combination and arrangement of parts as hereinafter more specifically described and illustrated in the accompanying drawings, wherein is shown an embodiment of the invention, but it is to be understood 35 that changes, variations and modifications can be resorted to which fall within the scope of the claims hereunto appended.

In the drawings wherein like reference characters denote corresponding parts 40 throughout the several views:

Figure 1 is a front elevation, with the sleeves broken away, of a shirt for outer wear in accordance with this invention.

Figure 2 is a section on line 2—2 Figure 1. 45 Figure 3 is a fragmentary view in elevation

illustrating the lower end of one of the sides of the body portion of the shirt.

The shirt includes a body portion referred to generally at 1, having its front provided with a vent opening of a length substantially 55 equal to two-thirds of the length thereof and further having its back closed. The length of the body portion is such that the lower end of the vent opening will be positioned at a substantial distance below the waist line 60 of the wearer of the shirt.

The shirt is illustrated by way of example as the collar attached type, the collar being indicated at 2. The shirt sleeves are designated at 3. The front of the body portion 65 1 is provided with a pair of pockets 4 capable of having the mouth ends thereof detachably closed by the conventional means, as indicated at 5.

The body portion 1 is formed of a closed 70 back section 6 and a slitted front section 7. The edges of the slit formed in section 7 are indicated at 8, 9 Figure 2.

The sections 6, 7 are of corresponding outline and with the upper portion of each side edge incurved to provide, when the sections are connected together in a manner to be presently referred to, a pair of arm-holes 75 through which extend the sleeves 3.

The sections 6, 7 are connected together for 80 a portion of the length of each side by a pair of rows of stitching 9, 10. At the lower end of that part of the connected portion of each side of the body portion 1, a gusset 11 is secured to said sections within the body portion. 85 See Figures 1 and 3. Rows of stitching 12 are provided for securing the sleeves 3 at the arm-holes of the body portion. Rows of stitching 13 are employed for connecting the top of the sections together from the sides of the neck 14 to the upper ends of the arm-holes. The sections 6, 7 below the gussets 11 are disconnected from each other. The sections 6, 7 are hemmed as indicated at 15.

Secured to the section 7 is a pair of oppositely disposed, opposed, lateral extensions 16, 17, the former overlapping and extended from the edge 8 and the latter overlapping and extending from the edge 9. The extensions 16, 17 are of a length to extend from 90 95 100

the neck 14 to below the end of the slit in section 7. The extensions 16 and 17 provide lateral continuations for the body portion 1 at the edges 8, 9 of the slit. The 5 extension 16 is arranged inwardly of the extension 17.

The extension 16 is what is termed a button carrying member and is formed from two narrow, independent, opposed strips 18, 19 10 of fabric of the desired length and width. The strip 18 is folded to provide throughout a central overlap 20 lengthwise thereof. The strip 18 is positioned against the inner face of section 7 and projects laterally with respect 15 to edge 8. The strip 19 is arranged against the outer face of section 7 and projects laterally with respect to edge 8.

The strips 18, 19 are secured together and to the section 7 by a row of stitching 21. The 20 strips 18, 19 are secured together exteriorly of edge 8, by a row of stitching 22. The overlap 20 in connection with strip 19 provides for four thicknesses of fabric through which extends the thread for securing a button 23 25 against the outer face of strip 19. Five buttons 23 are employed and they are arranged equi-distant apart.

The extension 17 is what is termed a button-hole member and is of greater width than the button carrying member. The extension 30 17 is formed of two narrow, independent, opposed strips of fabric 24, 25 of the desired length and width, the former being positioned against the inner face of section 7 and extended from the edge 9. The strip 25 is positioned against the outer face of section 7 and it projects from edge 9. The strips 24, 25 are secured together and to section 7 by a row of stitching 26. The strips 24, 25 are secured together exteriorly of edge 9 by a row of stitching 27. The strips 24, 25 are formed with lengthwise extending, registering, spaced 35 button-holes 28 for coacting with the buttons 23 for detachably connecting the button carrying member to the button-hole member 40 to provide the elongated vent 29.

The lower ends of the button carrying member and the button-hole member are secured together and to section 7 by the stitching 50 30.

The length of the slit in connection with extensions 16, 17 provides for increased ventilation and enables the shirt to be quickly positioned on the wearer. The gusset reduces the 55 splitting from the lower ends of the sides of the shirt body to a minimum. The overlap 20 provides an anchorage of increased thickness for the securing means for the buttons.

It is thought that the many advantages of 60 a shirt for outer wear in accordance with this invention can be readily understood, but although the preferred embodiment of the invention is as illustrated and described, yet it is to be understood that changes in the 65 details of construction can be had which fall

within the scope of the invention as claimed.

What I claim is:

1. A shirt including a body portion having its front formed with a slit of a length substantially equal to two-thirds of the body portion, inner and outer oppositely extending, opposed, lateral extensions overlapping and secured to the body portion, projecting from the edges of the slit and forming lateral continuations of said body portion and in connection with the slit providing a vent, each of said extensions formed of an inner and an outer independent, opposed strip secured together, the inner strip of said inner extension formed with a lengthwise extending overlap opposing the inner face of said body portion to provide an anchorage of increased thickness for the securing means of a set of buttons to be positioned against the outer strip of such extension, and the other of said extensions having a set of button-holes for the passage of the buttons. 70 75 80 85

2. A shirt including a body portion having its front formed with a slit of a length substantially equal to two-thirds of the body portion, inner and outer oppositely extending, opposed, lateral extensions overlapping and secured to the body portion, projecting from the edges of the slit and forming lateral continuations of said body portion and in connection with the slit providing a vent, each of said extensions formed of an inner and an outer independent, opposed strip secured together, the inner strip of said inner extension formed with a lengthwise extending overlap opposing the inner face of said body portion to provide an anchorage of increased thickness for the securing means of a set of buttons to be positioned against the outer strip of such extension, and the other of said extensions having a set of button-holes for the passage of the buttons, said outer extension being of greater width than said inner extension. 90 95 100 105 110

In testimony whereof, I affix my signature hereto.

MONTFORD M. MOORE.
